TUNING MECHANISM

Alfred G. Wheller, Los Angeles, Calif.

Application August 22, 1933, Serial No. 686,288

9 Claims. (Cl. 250—20)

My invention relates to automatically controlled tuning mechanisms for use in connection with the customary forms of variable condensers of radio tuning circuits.

5 In tuning circuits of the type employing variable condensers, it is common in the art to mount the movable plates of the condenser on a rotary, manually actuated shaft in order that the said movable plates may be adjusted relatively to the 10 co-operable fixed plates to thereby change the capacity of said condenser. The supporting shaft for the said movable plates is generally equipped with a dial on which a wave-meter scale is formed and said dial co-acts with a pointer to 15 indicate an intended angular position of the movable plates relatively to said fixed plates. Mechanism such as briefly referred to above is capable of being freely actuated manually at any and all times so that the instrument may be tuned for 20 reception of sound transmitted on a known wave length.

In carrying my invention into practice, it is not intended to depart from the common structural and functional characteristics of a radio 25 tuning set of the type above referred to. To the contrary, I propose to retain these features and qualities in order that the radio set may be tuned manually as and when desired. That is to say, it is an important object of my invention to employ 30 all of the above named instrumentalities in conjunction with automatically controlled mechanism by means of which a particular pre-selected tuning of the set may be effected at a predetermined future time, thus leaving the normal 35 tuning mechanism free for manual actuation at the pleasure of the user.

While I have referred to a use of the invention in conjunction specifically with sound instruments such as radio receiving sets, I shall have it 40 clearly understood that this reference is not by way of limitation, as it is proposed that it be used in combination with any transmitting mechanisms such, for instance, as employed in the art of television.

45 An important feature of the invention resides in the novel combination of respective tuning mechanisms, one of which is capable of manual adjustment at any time, regardless of the time 50 when the other thereof shall automatically function in response to a predetermined setting of same.

Another object of the invention is to provide a novel order and relationship of working parts 55 which need not require that changes be made in

the circuit in which same are intended to function.

A still further object of the invention is to provide cooperable tuning mechanisms which can be 5 easily controlled.

A still further object of the invention is to provide an automatic time controlled tuning mechanism which will operate with a high measure of 10 efficiency and accuracy and allow for fine or close tuning.

Another object of the invention is to provide a combination of independently functioning tuning mechanisms which may be compactly arranged in the instrument, in which same shall be used.

Another object is to provide co-operable mechanism of the kind stated which shall be of extremely simple construction, and aside from being positively acting, will possess such features and advantages as would be expected to prevent 15 same from being rendered inoperative or unreliable of action by frequent operation thereof.

A still further object of the invention is to provide respective co-operable tuning mechanisms whose actuations may be effected easily and 20 quickly by any person desiring to make use thereof, and to arrange said mechanisms in a way that will not detract from the general beauty and 25 design of a cabinet of which they shall become a part.

The invention consists in the novel construction, arrangement and combinations of parts as 30 hereinafter described and claimed.

Reference is to be had to the accompanying 35 drawings forming a part of this specification, in which similar characters of reference indicate corresponding parts in all the views.

In the drawings:

Figure 1 is a section taken horizontally through the front wall of a radio cabinet showing the 40 respective tuning mechanisms in operative association with the rotary shaft which carries the adjustable plates of a variable condenser;

Figure 2 is a front view of the respective mechanisms showing same set for tuning of the circuit on respectively different wave lengths at 45 respectively different times;

Figure 3 is a view partly in front elevation and partly in section of certain of the parts of the time controlled or automatic mechanism;

Figure 4 is a schematic perspective view showing the respective elements or main working parts as they would appear when separated from each other but in an order relatively to each other as 50 would indicate a pre-setting of one of the tuning 55

mechanisms and a neutral condition of the other or time controlled mechanism;

Figure 5 is a view in front elevation of the respective dials showing a modified form of setting means therefor.

In the accompanying drawings 1 represents the front wall of a radio cabinet in which is journaled for rotation a shaft 2 having a knob 3 by means of which the shaft can be actuated. 10 This shaft is adapted to constitute a part of any suitable well known form of variable condenser (not shown). I wish to make it clear that I am not interested in any special construction of condenser, and means for changing the capacity 15 thereof. Adjustment thereof can be provided for by any suitable well known means that may suggest itself to any person skilled in the art. The means employed, however, is suitable in every respect and where such shaft 2 is employed, it 20 obviously follows that same shall function as a mounting or support for the customary adjustable plates of the condenser, whereby said plates can be adjusted relatively to the coacting fixed plates of said condenser.

25 Fixed at 4 to the shaft 2 is a dial 5 on the front face of which is a wave meter scale 6, adapted to be viewed from a sight opening 7 in the wall 1, and to coact with a pointer 8 which is disposed above said opening. In this manner, it follows 30 that the dial 5 can be turned at will for ordinary tuning purposes. In one-half of the dial 5 is formed a semi-circular slot 9 whose purpose will be explained after a brief description of the several structural features has exhausted itself.

35 To this point in the description I have set forth essentially those elements required for an ordinary manual tuning of the receiving set, and to this extent said elements mutually contribute to produce one of the tuning mechanisms of the 40 system, the general scheme of which is of particular interest to me. The remaining one of the mechanisms of the system I will now proceed to describe, in so far as concerns the essential structural characteristics thereof.

45 In front of the dial 5 is a somewhat smaller dial 10, which, when placed in the position shown in Figure 2, will not obscure the wave-meter scale 6 of the aforementioned dial 5. This last said dial is formed to provide a semi-circular slot 11, 50 the latter occupying approximately one-half of the dial or that portion thereof which is situated at one side of the horizontal axis thereof, and, as illustrated, said dial is formed at its horizontal center with a bearing opening 12 whose diameter 55 is considerably greater than the diameter of the shaft 2 which passes therethrough. On the front face and in the other half of the dial 10 is a wave-meter scale, indicated at 13, and like the scale 6 of the dial 5, the markings thereon range from 60 0° to 100° , although this may obviously be modified without departing from the spirit and intention of the invention. The peripheral face of the dial 10 is formed with worm teeth 13a designed to intermesh with a manually controlled 65 worm gear 14. This worm gear is carried by a shaft 15 mounted behind the wall 1, and same has a bevel pinion 16 which meshes with a like pinion 16 on a control shaft 18. The dial 10 is very closely related to the dial 5 and its wave-meter 70 scale 13 is intended to be read through a window opening 19 in the wall 1 and to coact with a pointer 20.

75 Interposed between the dials 5 and 10 are flat disks 21 and 22, the former having a cylindrical hub 23 accommodated in the aforementioned

bearing opening 12 in the disk 10 and having a bearing passage 24 in which the shaft 2 is adapted to freely rotate so that adjustment of the dial 5 may be effected whenever desired. In one half of the peripheral face of the disk 21 I provide 5 ratchet teeth 25, and extending transversely through the disk is a semi-circular slot 26.

The peripheral face of the disk 22 is formed with a semi-circular series of ratchet teeth 27, and extending transversely through the disk 22 is 10 a semi-circular slot 28. To the extent thus far described, it is obvious that the disks 21 and 22 are similar to each other. Projecting from the front face of the disk 21 is a pin 29 which enters the slot 11 in the dial 10 and at the rear face of 15 said disk 21 is a pin 30 of a length to pass through both the slot 28 in the disk 22 and the slot 9 in the dial 5. On the front face of the disk 22 is a 20 forwardly extending pin 31 of a length to pass through both of the slots 11 and 26 in the dial 10 and said disk 21, and on the rear face of said disk 22 is a pin 32 which extends into the slot 9 in the dial 5.

The disk 21 is formed with an internal gear 33 and meshing therewith and with an external gear 34, the latter formed on the periphery of a spring drum 35, is a gear pinion 36. The said gear pinion 36 is mounted on a stud 37 which extends forwardly from the front face of the disk 22. Contained in the drum 35 is a convolute spring 38, 30 one end of which is attached to a pin 39 on the said disk 22 and the other end attached to the hub 40 of said drum, whereby the disk 21 will be urged in a clockwise direction by said spring and the disk 22 in a counterclockwise direction. 35 Spring-pressed dogs 41 and 42 coact with the respective ratchet faces 25 and 27 of the disks 21 and 22, and said dogs are formed with an armature 43. Because of the fact that the ratchet teeth 27 are reversely inclined relative to the teeth 25, it follows that the latching ends of the said 40 dogs are respectively oppositely beveled. Co-operable with the armature 43 is an electro-magnet 44 which, when energized, will retract said dogs from their respective ratchet faces on said disks 45 21 and 22. This magnet may be connected in any suitable well known electrical circuit, such as is conventionally illustrated at A, which said circuit includes a time-controlled mechanism B. It is in this manner that the dogs 41 and 42 will be 50 released at a predetermined time. The circuit A may also include a manually actuated switch C for breaking same, when desired. I show these dogs and their co-acting ratchet surfaces as one operative known mechanical means for releasing 55 said disks 21 and 22, and for enabling said disks to respond to the action of said spring 38. It will accordingly be understood that any approved well known means may be substituted therefor within the scope of the hereto appended 60 claims. I have now set forth the details of construction of the second or so-called time-actuated tuning mechanism herein employed, and shall, therefore, proceed to briefly describe the operation 65 of said second mechanism and shall illustrate how it co-acts with the first or so-called manually controlled mechanism for the purpose of satisfying the several objects elsewhere referred to herein.

On reference to Figure 4 of the drawings, it will be noted that the dial 10 of the time-controlled 70 mechanism by chance occupies a position where its wave-meter scale 13 registers 50° at the pointer 20, at which time the slot 11 in said dial occupies a position where the end walls 11a and 11b of said slot 11 will be substantially horizon- 75

tally alined so that the pin 29 of the next adjacent disk 21 will directly bear against the end wall 11a of said slot. The slot 9 in the disk 5 will substantially occupy the position shown in said Figure 4 so that the pin 32 of the disk 22 will engage against the end wall 9a of the slot 9 in said dial 5, as will be clearly understood. The dial 5 has its wave-meter scale also adjusted so that the 50° marking thereon will register with its co-acting pointer 8. This, we may assume, was done intentionally. The pin 31 of the disk 22 will engage with the closed end 26a of the slot 26 in the disk 21 and with the closed end 11b of the slot 11 in the dial 10, and the pin 30 on the disk 21 will bear against the closed end 9b of the slot 9 in said dial 5 and against the closed end 28a of the slot 28 in the disk 22. We will assume that the dials 5 and 10 occupy the positions shown in Figure 4 as a mere coincidence. Now let us assume that it is intended that the radio receiver be manually set for a reception on a wave length of 50° of dial 5 and that it is intended that the time controlled dial 10 be set for tuning in at a future time on a wave length of 70°, as illustrated in Figure 2. The operator simply rotates the dial 10 for such predetermined tuning, and in so doing the wall 11a of the slot 11 in said dial will press downwardly against the pin 29 of the disk 21 to thereby move the latter in a counterclockwise direction. When the limit of the desired adjustment of this dial has been reached, the dial will be effectively held in said position by its latching dog 42 which engages the ratchet surface 25. In like manner the surface 27 of the disk 22 will be engaged by its co-acting dog 41. After the dial 10 has been thus set the dial 5 may be turned as often and whenever desired, without in any manner disturbing the adjusted condition of the time responsive dial 10. The instrument B of the control circuit A of which the electro-magnet 44 forms a part may be set so that the circuit will be closed at a predetermined time, thus causing the said magnet to be energized, the armature 43 retracted, and the dogs 41 and 42 disengaged from their co-acting surfaces 25 and 27. The controlling means, consisting of the worm gears 13 and 14 and the intermediate gear pinions 17 and 18, is such that the dial 10 cannot be turned except by manual manipulation of said means. As stated, it so happens from the particular relative positions of the parts in Figure 4 of the drawings that with the dials 5 and 10 in the positions therein shown, the end wall 11a of the slot 11 in the dial 10 will be in direct engagement with the pin 29 on the disk 21 so that when the disk is turned counterclockwise, or in a direction towards the 70° marking on the dial, the disk 21 will be correspondingly turned. It also happens that in Figure 4 the pin 30 on the disk 21 is at the end 28a of the slot 28 in the disk 22, and that the pin 31 on the disk 22 is at the end 26a of the slot 26 in the disk 21. It will be further noted that the pin 32 of the disk 22 is directly engaged with the end wall 9a of the slot 9 in the dial 5. We can say, as elsewhere alluded to, that it is by chance that the aforeslated parts are in the positions just referred to, but let it be clearly understood that when any particular adjustment of the dial 10 for a predetermined tuning of the radio receiver is made the disks 21 and 22 will always be moved with said dial if by chance their pins 30 and 32 are in positions where they will be engaged by the end walls of said slot 11. With the dial 10 turned to cause the 70° marking of its scale 13 to register with its pointer 20, as shown in said Figure 4, the pin 29 of the disk 21 will directly bear against the end wall 11a of said slot 11.

ure 2, the mechanism is set and when the electro-magnet 44 is energized, the disks 21 and 22 will be released and the dial 5 will be moved to cause its 70° marking on its scale 6 to register with the pointer 8. After the dial 10 has been adjusted for a predetermined automatic tuning of the receiver at a future time, the dial 5 may be freely moved manually to any selected position as often as desired. It should be clearly understood, however, that when manually moving the dial 5 in one direction or another and after a setting of the dial 10 for automatically changing the tuning at a designated future time, the walls 9a and 9b will co-act with the respective pins 30 and 32, and relative movement will therefore be set up in the disks 21 and 22, thus tensioning the spring 38. Here, it will be noted that because the ratchet teeth 25 extend at an opposite angle to the teeth 27, the tension of the spring is retained until the dogs 41 and 42 are released from said teeth at a predetermined time.

In Figure 5, the dials 5a and 10a correspond with the dials 5 and 10. The dial 10a is provided with an annular series of worm teeth 45 and a co-acting manually controlled worm gear mechanism 46, the latter being like the worm gear mechanism which I stated co-acted with the dial 10. The dial 5a has an annular series of gear teeth 5b which mesh with a manually actuated spur gear 5c.

While I have shown the invention applied to a receiver of the kind employing tuning dials, it is to be understood that I do not wish to be limited in this respect.

It is believed that the simplicity of the invention is self-evident and that it will be appreciated that same may be readily adapted to many forms of radio receiving instruments now in general use.

Having now fully described both the functional and structural features of the invention and the manner in which the invention can be carried into effect and operated by one ordinarily skilled in the art, what I claim as my invention is:

1. Tuning mechanism for radio receivers comprising a manually actuatable tuning dial; a resetting dial having its supporting axis co-incident with that of the first dial and mounted to turn independently of said first dial; means co-operable with both dials and controlled by an actuation imparted to the resetting dial for predeterminedly resetting the first dial; and means actuatable by the resetting dial for rendering the co-operable means active for a resetting of said first dial at the expiration of a predetermined period of time.

2. Tuning mechanism for radio receivers comprising a manually actuatable tuning dial; a resetting dial having its supporting axis coincident with that of the first dial and mounted to turn independently of said first dial; motion imparting mechanism co-operable with both dials and including resilient means whose tension may be varied by a predetermined manual actuation imparted to the resetting dial; means for holding said resilient means under tension; and means for automatically releasing the tension on said resilient means to thus render the motion imparting mechanism active for a resetting of said first dial.

3. Automatic tuning means for radio receivers comprising a plurality of independent, manually actuatable dials having corresponding co-operative graduations; time responsive mechanism operatively connecting one dial with the other for automatically changing the adjustment of said

other dial, according as the said one dial shall have been first manually turned to establish a pre-selected co-action of the dial with its pointer; and a condenser shaft to which the said other dial is fixed and about which the said one dial is free to turn.

4. Automatic tuning means for radio receivers comprising a plurality of independent, manually actuable rotary dials, said dials having co-operable graduations; time-controlled mechanism; means co-operable with the time-controlled mechanism for automatically adjusting one dial to a predetermined extent in response to a pre-selected setting of the other dial and including rotary disks, and means co-operable with the disks and said time-controlled mechanism to impart limited movement to said one dial in either a clockwise or a counter-clockwise direction at a predetermined time according as the said other dial shall have been previously adjusted manually for a pre-determined subsequent change of adjustment of said one dial.

5. Automatic tuning means for radio receivers comprising a plurality of independent, manually actuable rotary dials, said dials having co-operable graduations; one of the dials having an axial opening, a condenser shaft supporting the other dial and passing through said axial opening and having manipulating means positioned in front of said one dial; the said shaft serving to support the said one dial for free turning movement in either direction about the axis of said shaft; means operatively connecting the respective dials with each other for determining the extent of movement to be imparted to the other dial; and means co-operable with the connecting means to render same active to move said other dial at a predetermined time and to an extent determinable by a manual pre-setting of said one dial.

6. Automatic tuning means for radio receivers comprising a plurality of independent manually actuable rotary dials, said dials having co-operable graduations; one of the dials having an axial opening, a condenser shaft supporting the other dial and passing through said opening and having manipulating means positioned in front of said one dial; the said shaft serving to support the said one dial for free turning movement in either direction about the axis of said shaft; means operatively connecting the respective dials with each other for determining the extent of movement to be subsequently imparted to said

other dial; means co-operable with the connecting means to render same active to move said other dial at a predetermined time and to an extent determinable by a pre-setting of said one dial to a selected position; and gear means for setting said one dial to thus act upon the connecting means for the aforementioned subsequent turning of the other dial.

7. In means for automatically resetting the tuning dial of a radio receiver, a pair of oppositely rotatable disks; means for holding the disks against rotary movement in one direction; means for releasing the holding means from the disks and for imparting predetermined rotary movement to the disks; the releasing and imparting means including a coil spring having one end fixed to one disk and its opposite end fixed to the other disk; and means for connecting the disks to the tuning dial of a radio receiver to reset same in response to movement of either disk.

8. In means for automatically resetting the tuning dial of a radio receiver, a pair of oppositely rotatable disks; means for holding the disks against rotary movement in one direction; means for releasing the disks from said holding means and for imparting predetermined rotary movement thereto; the releasing and imparting means including a coil spring having one end fixed to one disk and its opposite end fixed to the other said disk, an annular set of peripheral teeth on each disk, and time controlled dogs co-operable with the teeth of each disk; and means for connecting the disks to the tuning dial of a radio receiver to reset said tuning dial in response to movement of either disk.

9. In means for automatically resetting the tuning dial of a radio receiver, a pair of oppositely rotatable disks; means for holding the disks against rotary movement in one direction; means for releasing the disks from said holding means and for imparting predetermined rotary movement thereto; the releasing and imparting means including a coil spring having one end fixed to one disk and its opposite end fixed to the other said disk, an annular set of peripheral teeth on each disk, and time-controlled dogs co-operable with the teeth of each disk; and a graduated rotary dial for selectively tensioning said spring to render either disk operative for predetermined rotary movement.

ALFRED G. WHEELER.
